(57) **CLAIM**

The ornamental design for a jumper clamp, as shown and described.

DESCRIPTION

FIG. 1 is a top perspective view of a jumper clamp showing our new design.

FIG. 2 is a bottom perspective view of the jumper clamp of the present invention.

FIG. 3 is an elevation view of the jumper clamp of the present invention.

FIG. 4 is the opposite elevation view of the jumper clamp of the present invention.

FIG. 5 is a top view of the jumper clamp of the present invention.

FIG. 6 is a bottom view of the jumper clamp of the present invention.

FIG. 7 is a rear view of the jumper clamp of the present invention.

FIG. 8 is a front view of the jumper clamp of the present invention; and,

FIG. 9 is a top perspective view of the jumper clamp of the present invention with its jaws in an open position.

The broken lines shown represent portions of the jumper clamp that form no part of the claimed design.

1 Claim, 7 Drawing Sheets
